U.S. Cl. D32—1 R

FIG. 1

FIG. 2

FIG. 3

FIG. 4

FIG. 1 is a perspective view of a loop needle embodying the new design;

FIG. 2 is a top plan view thereof;

FIG. 3 is a side elevational view thereof; and

FIG. 4 is a cross section taken on line 4—4 of FIG. 2. The characteristic feature of our design resides in the external configurations of the loop needle as best illustrated in FIGS. 1, 2, and 3 in the drawing.

We claim:

The ornamental design for a loop needle, substantially as shown and described.
